TEST TUBE HOLDER

Hymen Shiller, Chicago, Ill.

Application September 29, 1938, Serial No. 232,374

6 Claims. (Cl. 294—131)

This invention relates to test tube holders, especially such holders as are adapted for use in manipulating a test tube over a flame or other heating means for heating the contents of the tube.

In making certain tests it is necessary to heat liquids in a test tube, frequently to the boiling point. Care must be taken to prevent an excessive heating or rate of heating, for otherwise the contents of the tube may reach the boiling point unexpectedly and be violently ejected from the tube. Such ejecting of the liquid results not only in the loss of the contents of the tube, but also may cause the boiling liquid to spill on the hands or even the face of the operator. Frequently the contents of the tube are ejected so violently as to spatter the walls and ceiling of the room. When the test is being performed by an unskilled operator the danger of such accidents is particularly great. Such tests must be made frequently in the home by unskilled people as, for instance, in making a test for the presence of sugar in the urine in the case of a diabetic. It is an object of the present invention to provide a test tube holder which may be used to hold and manipulate a test tube over an open flame or other heating means and which will positively prevent injury to the operator or damage to the room in the event that the contents of the tube are violently ejected. This result is accomplished, in the embodiment of the invention here illustrated, by providing a shield which extends over the top of the test tube but is sufficiently spaced therefrom to permit the free rapid ejection of the contents of the tube, should the contents be forced outwardly by the heat or other causes. The shield prevents spattering on the walls or ceiling of the room, or upon the hands or face of the operator.

It is a further object of the present invention to provide a test tube holder which shall be reliable in its operation and simple and economical in construction.

The attainment of the above and further objects of the present invention will be apparent from the following specification taken in conjunction with the accompanying drawing forming a part thereof.

In the drawing:

Figure 1 is a plan view of a test tube holder embodying the present invention;

Figure 2 is a side view thereof showing the position of a test tube in dotted lines;

Figure 3 is a bottom view of the holder; and

Figure 4 is a sectional view taken along the line 4—4 of Figure 2.

The test tube holder, indicated in general by the reference numeral 1, comprises two flat metal springs 2—3, which are riveted together at one end by a rivet 4, and are adapted to be spread apart at their opposite end for receiving and holding a test tube 5. To facilitate holding of the test tube the spring members 2—3 are each provided with a jaw 7—8. The two jaws 7—8 are adapted to be spread apart so that a test tube may be inserted between the jaws. Upon release of the jaws, they spring back and firmly grip the tube. A bead 10 at the top of the test tube rests on the springs 2—3, thereby supporting the tube 15 against downward retraction.

A metal strap 13 embraces the flat spring members 2—3 and is slidable along the spring members. By sliding the strap 13 towards the jaws 7—8 the flat spring members 2—3 are drawn 20 into firmer engagement with the test tube, thus preventing accidental spreading of the jaws 7—8 to permit dropping of the test tube. To release the test tube, the strap 13 is pushed back to the position illustrated in Figures 2 and 3 and the jaws spread apart manually, thereby permitting 25 the free withdrawal of the tube between the jaws.

A shield 15 is pivoted to the flat spring metal members 2—3 by the rivet 4, so that the shield may be swung about the rivet 4 with respect to the spring metal members 2—3. The shield 15 includes a handle portion 16 and a cover shield member 17 which extends over the top of the test tube but is sufficiently spaced therefrom to permit the free egress of the contents of the tube should they suddenly commence to boil violently. The cover 17 is joined with the handle portion 16 by a vertical part 18. The handle portion 16 is generally U-shaped in cross section, as may be seen from Figure 4. The arms 19 and 20 of the U-shaped handle portion loosely embrace the flat spring members 3—4. The handle portion 16 is of a minimum width adjacent the rivet 4 where the arms 19—20 are flat against and press upon the spring members 3—4, and gradually tapers to a maximum width adjacent the vertical part 18. The entire shield member 15 may consist of a piece of sheet metal bent to the requisite shape.

The rivet 4 causes the sides 22 of the handle portion 15 to exert a small amount of pressure 50 against the springs 2—3 so that the friction between the sides and the flat spring members 2—3 is sufficient to hold the handle and the spring in their relatively adjusted positions. The test tube holder may then be held by means of the handle 55

15 by causing the hand to embrace the handle and the spring members 2—3, or by merely gripping the sides 19—20 of the handle with the thumb and two adjacent fingers. The test tube is thus held in position and may be manipulated over an open flame with safety. If the contents of the tube should be violently ejected, the cover 17 will prevent splashing of the contents of the tube against the wall or ceiling of the room, and together the vertical portion 18 and the sides 19—20 of the handle portion will effectively prevent spattering of the boiling contents of the tube against the hands or face of the operator.

It is to be noted that the cover 17 is inclined 15 downwardly at a slight angle. This, together with the curvature of the cover, helps to prevent spattering of the contents thereof sideways. The vertical portion 18 affords greater protection against spattering of the contents rearwardly towards the hand of the operator holding the test tube holder. It is thus apparent that if the contents of the tube should be violently ejected there is no danger 20 to the operator and no possibility of the contents spattering against the walls or ceiling of the room.

25 In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

30 1. In combination, means for releasably holding a test tube for manipulation over a flame, and a shield extending over the top of the tube but spaced therefrom to permit the free egress of vapors from the tube.

35 2. In combination, means for releasably holding a test tube for manipulation over a flame, and a shield extending over the top of the tube but spaced therefrom to permit the free egress of vapors from the tube, said tube holding means and said shield being hinged together.

40 3. Test tube holding and manipulating means comprising a pair of jaws adapted to embrace the top of a test tube and exert a spring pressure thereagainst and including a portion extending at right angles to the longitudinal axis of the tube, a shield over the top of the tube, said shield including an arm extending to the end of said jaw portion remote from the jaws, means pivotally joining said arm to said portion to permit changing of the distance between the shield and the 45 jaws, said shield being held in a position spaced from the top of a test tube to permit free egress of vapors from the tube.

4. Test tube holding and manipulating means comprising a pair of juxtaposed flat spring metal members having cooperating jaws at one end adapted to be spread apart to embrace and hold a test tube, said spring members being secured together at their opposite ends, a shield member including a portion nestled with said spring members at said opposite end and pivotally joined thereto, said shield member extending above the jaws an amount sufficient to space it from the top of a test tube held by the jaws and being held in place by the frictional engagement of the relatively movable parts.

5 5. Test tube holding and manipulating means comprising a pair of juxtaposed flat spring metal members having cooperating jaws at one end adapted to be spread apart to embrace and hold a test tube, said spring members being secured together at their opposite ends, a shield member including a portion nestled with said spring members at said opposite end and pivotally joined thereto, said shield member extending above the jaws an amount sufficient to space it from the top of a test tube held by the jaws and being held in place by the frictional engagement of the 10 relatively movable parts, said shield member including a portion embracing the sides of the spring metal members and also overlying the top thereof, and said spring metal members including a strap movable along the members and limiting the spreading of the members for causing the spring pressure against a test tube.

15 6. Test tube holding and manipulating means comprising a pair of juxtaposed flat spring metal members having cooperating jaws at one end adapted to be spread apart to embrace and hold a test tube, said spring members being secured together at their opposite ends, a shield member including a portion nestled with said spring members at said opposite end and pivotally joined thereto, said shield member extending above the jaws an amount sufficient to space it from the 20 top of a test tube held by the jaws and being held in place by the frictional engagement of the relatively movable parts, said shield member including a portion embracing the sides of the spring metal members and also overlying the top thereof, and said spring metal members including a strap movable along the members and limiting the spreading of the members for causing the spring pressure against a test tube.
